United States Patent Office

Des. 191,702
Patented Nov. 7, 1961

191,702

TRACTOR

Theodore H. Koeber, Barrington, and William J. Askins,
Park Ridge, Ill., assignors to The Frank G. Hough
Co., a corporation of Illinois

Filed Aug. 5, 1960, Ser. No. 61,634

Term of patent 14 years

(Cl. D14—3)

Fig. 1.

Fig. 2.

Des. 191,702

PAGE 2

Fig. 3.

Fig. 4.

FIGURE 1 is a right-side elevational view of a tractor, showing our new design;

FIGURE 2 is a three-quarter perspective view of the right front portion of the tractor of FIGURE 1;

FIGURE 3 is a rear elevational view of the tractor of FIGURE 1;

FIGURE 4 is a top plan perspective of the tractor of FIGURE 1 with the cab removed;

FIGURE 5 is a left side elevational view of the tractor of FIGURE 4; and

FIGURE 6 is a view similar to FIGURE 2 but with the cab removed.

The essential features of our design reside in those portions shown in full lines.

We claim:

The ornamental design for a tractor, as shown and described.
